UNITED STATES PATENT OFFICE.

EDWARD ROLFE, OF MOUNT SAVAGE, MARYLAND.

APPARATUS FOR VENEERING BRICKS.

SPECIFICATION forming part of Letters Patent No. 772,828, dated October 18, 1904.

Application filed May 24, 1904. Serial No. 209,500. (No model.)

To all whom it may concern:

Be it known that I, EDWARD ROLFE, a subject of the King of Great Britain, residing at Mount Savage, in the county of Allegany and 5 State of Maryland, have invented new and useful Improvements in Apparatus for Veneering Bricks, of which the following is a specification.

This invention relates to an apparatus for 10 veneering or covering one or more sides of a bar of clay as it emerges from the forming-tube of a clay-working machine, which is afterward cut up into bricks, tiles, or other articles capable of being made from clay molded 15 in bar form.

The common method of coating bricks and other clay products with engobe—a mixture of clay and coloring-matter—is to immerse them by hand repeatedly in a watery mixture 20 of engobe, allowing them to dry between each immersion. A bar of clay has also been coated with engobe in a thick plastic condition by applying it to the surface of the clay bar as it emerges from the forming-die, the 25 clay bar and engobe passing through an opening in a plate called a "slicker," which spreads the engobe evenly over the surface of the bar.

The object of my invention is to improve 30 this form of apparatus for applying engobe by making the slicker vertically adjustable with reference to the clay bar, that the coating of engobe may be regulated in thickness and forced to adhere positively to the surface of the bar of clay. My slicker is adapted for 35 application to any form of machine making a continuous clay bar. It may also be applied to a table over which the clay bar passes. The adjustment of the slicker can also be readily made or the slicker entirely removed 40 without stopping the machine.

Referring to the drawings, Figure 1 represents a front elevation of a clay-bar-forming machine with my improvement applied thereto. Fig. 2 is a plan view thereof. Fig. 3 is 45 a diagrammatic view showing the application of engobe to a clay bar in connection with my invention.

Similar letters refer to the same parts on the several figures.

A indicates the cylinder of a clay-bar machine with a filling-hopper B and a mouth or forming-tube C, by which the outgoing bar D of clay receives its shape.

E E are two rods, preferably square in cross-section, attached to the flange e of the 55 mouthpiece C in its horizontal diameter. The rods E extend forwardly beyond the mouthpiece or forming-tube C for a suitable distance and support a slicker F.

As shown in Fig. 1, the slicker F has a top 60 f and two sides f' f', which surround three sides of the clay bar D. Projecting laterally from each side f' f' is a flange f'', through which are formed vertical slots f''' for the rods E to pass through. Bolts G, threaded into 65 the flanges f'' f'' at their tops and bottoms, pass into the slots and bear against the upper and lower surfaces of the rods E. When the bolts G are turned in well-known manner, the slicker F will be raised from or brought closer 70 to the clay bar D. The proper space between the slicker and the clay bar having been obtained, the bolts G are tightened on the rods E, fastening the slicker in place.

Reference to Fig. 3 will show that the top 75 f of the slicker lies at an angle to the surface of the clay bar D, the rear edge being higher than its forward edge. As thus arranged the engobe deposited on the clay bar and brought beneath the slicker is pressed against the bar 80 of clay and forced to adhere closely thereto, the forward edge of the slicker regulating the thickness of the veneer coating. The consistency of engobe is such that the non-adhering portion rolls backwardly as the bar advances.

The clay bar after being treated as above described is cut up into suitable lengths for commercial use.

Having thus described the invention, what 90 is claimed as new is—

1. In an apparatus for veneering or coating bricks and the like, a clay-bar-forming machine, combined with an engobe-applying

form or slicker, rods projecting from said machine, supporting said engobe-applying plate or slicker, and means for adjusting the said plate or slicker on said rods.

5 2. In an apparatus for veneering or coating bricks and the like, a clay-bar-forming machine, combined with an engobe-applying form or slicker, rods projecting from said machine, supporting said slicker, perforated

flanges on said slicker through which said rods pass, and bolts threaded in said flanges bearing against said rods.

In testimony whereof I affix my signature in presence of two witnesses.

EDWARD ROLFE.
